(57) **CLAIM**

The ornamental design for a party light, as shown and described.

DESCRIPTION

FIG. 1 is a first perspective view of a party light showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion 9 in FIG. 1.

The evenly dash broken line showing in the drawings is included for the purpose of illustrating unclaimed portions of the party light and forms no part of the claimed design. The long and short dash broken line is for the purpose of depicting the boundary lines of the enlarged view shown in FIGS. 1 and 9, and form no part of the claimed design.
